FIG. 1 is a perspective view of a modified tetrahedral neutral converter, showing our new design;

(56) **References Cited**

FIG. 2 is a top plan view thereof, showing the vertical and horizontal symmetry of the design;

U.S. PATENT DOCUMENTS

FIG. 3 is a bottom plan view thereof;

FIG. 4 is a front elevation view thereof;

3,562,077 A 2/1971 Raba

FIG. 5 is a back elevation view thereof, which because of the vertical and horizontal symmetry of the design, is a mirror image of the front elevation view;

D258,743 S 3/1981 Ruga

FIG. 6 is a left side elevation view thereof, which because of the vertical and horizontal symmetry of the design, is a rotation from the front elevation view; and,

D258,744 S 3/1981 Ruga

FIG. 7 is a right side elevation view thereof, which because of the vertical and horizontal symmetry of the design, is a mirror image of the left side elevation view.
